UNITED STATES PATENT OFFICE.

MATTHEW GOLLUB, OF PHILADELPHIA, PENNSYLVANIA.

HAIR-PIN.

Specification of Letters Patent. Patented June 11, 1918.

1,268,959.

Application filed September 21, 1917. Serial No. 192,607.

To all whom it may concern:

Be it known that I, MATTHEW GOLLUB, a citizen of the United States, residing at Philadelphia, in the county of Philadelphia and State of Pennsylvania, have invented 5 certain new and useful Improvements in Hair-Pins, of which the following is a specification.

One object of my invention is to provide 10 a hair pin which will have a portion or portions so formed as to permit the easy movement of the pin into the hair, but will act as a check or lock to prevent the outward movement of the pin from the hair. Thus, a pin 15 made in accordance with my invention will not accidentally fall out of the hair after once being inserted into the desired position.

A further object is to make my improved 20 hair pins of comparatively simple construction and so that they can be manufactured and sold at a reasonably low cost.

These objects, and other advantageous 25 ends which will be described hereinafter, I attain in the following manner, reference being had to the accompanying drawing.

The head 42 of the hair pin has an extension 30 41 springing outwardly therefrom, said extension being bent in the direction of one of the sides or tines 43 of the pin, the bent 35 portion 44 of said extension being spaced beyond the outer end of the head to provide a recess 45 into which hair can enter from the side. A pin made in accordance with my invention can be initially inserted 40 into the hair up to the full extent of the head of the pin so that practically the entire length of the pin can be inserted within the hair. Furthermore, the pin can be easily inserted within or removed from the 45 hair with one hand since there are no parts which actually pinch the hair or which require a severe or different pushing movement to insert the pin within the hair.

It will thus be understood that a hair pin 50 made in accordance with my invention can be freely and easily inserted within the hair, the function of the above described extension and recess not coming into play until the pin attempts to move outwardly. However, after the pin has been inserted entirely

within the hair, any attempt of the pin to accidentally move outwardly will be checked by the hairs which will enter the recess 44 from the side and will be held between the head 42 and the extension 41.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:

1. A hair pin having an extension springing outwardly from its head and bent in the direction of the side of said pin, said extension being spaced beyond the outer end of the head to provide a recess into which hair can enter from the side, substantially as described.

2. A hair pin having an extension springing outwardly from the head from a point located at one side of the central plane passing between the sides of the pin, said extension being bent, from said springing point, in the direction of the side farthest removed therefrom, said extension being spaced beyond the outer end of the head to provide a recess into which hair can enter from the side, substantially as described.

3. A hair pin having an extension springing outwardly from its head and bent in the direction of the side of said pin, said extension being spaced beyond the outer end of the head to provide a recess into which hair can enter from the side, said extension being made integral with the portion of said pin which forms the head, substantially as described.

In testimony whereof I have signed my name to this specification in the presence of 95 two subscribing witnesses.

MATTHEW GOLLUB.

Witnesses:

CHAS. E. POTTS.

Copies of this patent may be obtained for five cents each, by addressing the "Commissioner of Patents, Washington, D. C."

It is hereby certified that in Letters Patent No. 1,268,959, granted June 11, 1918, upon the application of Matthew Gollub, of Philadelphia, Pennsylvania, for an improvement in "Hair-Pins," errors appear in the printed specification requiring correction as follows: Line 42, for the word "different" read *difficult*; line 77, claim 2, for the article "the" read *a*; and that the said Letters Patent should be read with these corrections therein that the same may conform to the record of the case in the Patent Office.

Signed and sealed this 2d day of July, A. D., 1918.

[SEAL.]

F. W. H. CLAY,

Acting Commissioner of Patents.
